UNITED STATES PATENT OFFICE.

JAROSLAV BENDA, OF PRAGUE, CZECHOSLOVAKIA.

LAST.

Application filed October 11, 1924, Serial No. 743,140; and in Czechoslovakia October 19, 1923.

The object of the present invention is to produce boots and shoes having a concave support for the foot, and the invention consists in providing for this purpose a last 5 having a bottom surface comprising a middle portion which is substantially flat in cross section and a substantially flat margin extending entirely around the last except at the inside of the shank, the margin being upwardly inclined relative to said middle portion.

Fig. 1 of the accompanying drawings represents a vertical section of the improved last, taken on the line I—I of Fig. 2,

15 Fig. 2, a bottom view of the last,

Fig. 3 is a section across the seat portion of the last taken on the line III—III,

Fig. 4, a section across the shank portion taken on the line IV—IV,

20 Fig. 5, a section across the joint portion taken on the line V—V all of Fig. 2,

Fig. 6 is a section across the seat portion of a modified form of the last,

Fig. 7, a section across the joint portion 25 showing a similar modification,

Fig. 8 is a bottom view of a last which is shod with metal,

Fig. 9, an incomplete bottom view showing a metal shoe of modified construction,

30 Fig. 10 is a section on the line X—X of Fig. 8,

Fig. 11, another section showing the metal shoe applied in a different manner, and

35 Fig. 12 is a diagrammatic view on a larger scale showing the cross-sectional outline of the last at the joint.

In order to provide a concave support for the foot, the boot or shoe last 1 is formed at 40 the bottom with a margin 3 which is carried entirely around the last except at the inside of the shank and which is set at an angle α corresponding approximately to the slope of the sole of the foot, to the middle portion 2.

45 The chamfering of the last which produces the margin 3 provides accommodation for the various connecting elements and allows the insole to lie in direct contact with the sole so that, while the foot will be supported by a surface which is more in conformity with its shape, the filling material usually introduced between the soles will be obviated, the weight of the footwear being correspondingly reduced.

50 The cross-sectional outline of the surface 2, except at the shank, and also that of the

margin 3, is substantially straight, but both may be slightly convex or concave according to need and requirements. The edge 5 between the margin and the surface 2, and the edge 4 between the margin and the upper part of the last, can either be sharp as indicated in the drawings or rounded off so that the different surfaces will merge gradually into each other. 65

The surface 2 may either be horizontal as shown in Figs. 3 and 5, or inclined in either direction, as shown in Figs. 6 and 7 according to whether the weight of the user of the footwear is uniformly distributed over the 70 width of the sole or displaced towards one side or the other. By this arrangement uniform wear of the sole and the heel can be ensured in all circumstances.

When the bottom of the last is provided with a metal facing, this is only applied to the surface 2 either in the form of a continuous plate 11, as shown in Fig. 8, or in the form of a horseshoe plate 15 which follows the edge 5, as shown in Fig. 9. The 75 plates are secured by means of screws 12 or the like and are either let into the wood, as shown in Fig. 10, or formed with chamfered edges 14, as shown in Fig. 11, so as to merge into the wood surface. The metal facing may, as an alternative, be applied to the last in the form of a spray. 80

The heel portion of the last is according to the invention traversed vertically by a sleeve 16 which is screwed through a bore 8 in the last. To lock this sleeve to the last, one end of it is formed with a flange 18, the other end is, after the sleeve has been screwed through the last, flared or upset against the wood as shown at 17. The 85 flange 18 may be made wide enough to take fastening screws 19, as shown in Fig. 1. The sleeve 16 strengthens the last and prevents it from splitting under the action of the heel nailing machine. 90

The last may be formed out of an existing conventional last by applying to the latter, so as to form the surface 2 and the margin 3, a suitable filling of leather, fibre, wood or other suitable material. 100

The angle α is generally about 20° but it may be varied according to circumstances, and it need not be uniform entirely around the last. At the back of the seat, and at the toe, for instance, where, owing to the acuteness of the curve, a considerable accumulation of leather occurs, the angle may be 110

somewhat increased. Such variation may also take place in respect of the width of the margin which is normally from one quarter to one fifth of the widest portion of the bottom surface of the last.

The diagram in Fig. 12 shows the plotting of the angles α relative to the horizontal p across the joint R. The broken line 7 indicates the plane in which the upper 10 is stitched to the insole.

Owing to the absence of filling between the soles, the foot can rest deeper in the shoe which can therefore be made smaller and neater than usual. At the same time the 15 shoe will be much more comfortable to wear.

I claim:

1. A boot last having a bottom surface comprising a middle bottom portion which

is substantially flat in cross-section, and a substantially flat margin extending entirely 20 around the last except at the inside of the waist, the margin being upwardly inclined relative to said middle bottom portion at an angle of substantially 20° , the width of the margin being substantially one quarter 25 of the widest portion of the bottom surface of the last, substantially as and for the purpose set forth.

2. The last structure claimed in claim 1 and a metal insertion arranged so as to define the boundary between the middle bottom portion and the inclined margin.

In testimony whereof I have signed my name to this specification.

JAROSLAV BENDA.
